S. H. SMITH

CONDENSER

Filed Jan. 16, 1925

UNITED STATES PATENT OFFICE.

SAMUEL HAROLD SMITH, OF ROCKY RIVER, OHIO.

CONDENSER.

Application filed January 16, 1925. Serial No. 2,785.

This invention relates to electric condensers.

This invention has utility when incorporated in adjustable condensers, especially in nicety of control in determined regions.

Referring to the drawings:

Fig. 1 is a side elevation, with parts broken away, of an embodiment of the invention in a condenser, as especially adapted for radio work;

Fig. 2 is a front elevation of the condenser of Fig. 1;

Fig. 3 is a partial section on the line III—III, Fig. 2;

Fig. 4 is a section of the line IV—IV, Fig. 2;

Fig. 5 is a detail view in perspective of one of the elements providing one of the series of faces; and

Fig. 6 is a view of a capacity-distance curve hereunder.

Insulation panel 1 is shown as having mounted thereon by screws 2, lugs 3 extending from housing 4 of general box form having closure lid 5 at the top thereon. Fixed with rear end 6 of this housing 4 and therein is member 7 having forwardly projecting wedges 8 providing adjacent faces 9, 10, converging. These faces as shown are of plane form and as adjacently approaching may be somewhat short of running into a feather edge therebetween.

This member 7 has terminal 11, externally threaded, upon which is mounted nut 12 for anchoring conductor or line 13 therewith. This member 7 has openings 14 therethrough extending from the side 6 of the housing 4. In each of these openings 14, herein shown as two in number, is insulation stem 15 upon which is loosely mounted member 16 opposing the member 7.

This member 16 is provided with a series of faces 17, 18, of plane form and approximately parallel respectively with the faces 9, 10. This member 16, as movable on the insulation guide rods 15 has its distance from the member 7 adjusted by stem 19 having threaded engagement with the member 16, and held by collar 20 against axial movement as to front end 21 of the housing 4.

Accordingly, rotation of this stem 19 in one direction will cause the member 16 to move toward the member 7 and thus reduce the distance between the parallel faces 9, 17, and the parallel opposing faces 10, 18. Rotation of this stem 19 in the opposite direc-

tion will cause the distance between these opposing parallel faces to increase. As these faces move toward each other there is not only a reduction of the perpendicular distance between the faces as interfitting, but there is an increase in the area of the opposing face regions, thereby introducing an additional factor of capacity.

The rotation of this stem 19 may be effected through knob 22 as a speed reduction device for actuating pointer 23 over scale 24. Curve 25 having distance abscissæ 26 and capacity in microfarad as ordinates 27 shows that in the closer positions there is a more abrupt change in the rising line portion 28 of this curve 25. The angle between the faces 9, 10, or 17, 18, may be varied as to its acute, right angle, or obtuse extent, and by such variation the position of the knee 29 of the curve 25 may be given a different location, while the lesser degree change portion 30 may also be thus adjusted. In practice, it is found desirable to have this lesser degree change portion 30 the one for the operative range of the condenser in use. This means there is possible, great refinements in adjustment, which refinements in adjustment permit the niceties of tuning in and tuning out, in radio operations.

There is, accordingly, under this disclosure possible a simple device of capacity range involving the variable distance with the variable of area selectively possible in a combination for answering the most delicate requirements of use.

This housing 4 as installed is preferably charged with a liquid, as castor oil 31 as a factor in increasing the condenser effect and stabilizing the condenser against disturbance by atmospheric conditions.

The stem 19, as conductor connected to the member 16, has its collar 20 effect packing with the housing wall 21 against leakage of the castor oil 31 therethrough. The opposite electrical connection to the one from the member 7 may be effected by circuit from the member 16 through the stem 19. Insulation mounting of the knob 22 precludes ground from such source, and conductor action may be by way of the housing wall 21 through the housing 4 to terminal 32 in the rear wall 6 having nut 33 thereon for connecting line 34. Insulation base 35 and insulation washer 36 for the terminal 11 and mounting of the member 7 separate these electrical connections of this condenser.

What is claimed and it is desired to secure by Letters Patent is:

1. An electric condenser comprising opposing series of interfitting wedge faces, insulation guide means protruding from one series and through the other series, rotatable adjusting means for propelling one series on said guide means toward the other, a housing for the members, castor oil in said housing extending between said faces, a terminal for one series of faces connected through the adjusting means and mounted on said housing, a terminal for the other series directly mounted on said other member, and a packing for the adjusting means as passing into the housing.
2. In a radio receiving set having a con-

trol panel, a housing mounted by the panel having an insulation wall, a pair of condenser elements having interfitting faces, one of said elements mounted by the insulation wall, an insulation guide bar extending in said housing on which the second element is movable as to the wall mounted element, rotatable adjusting means for propelling the movable element as to the other element, said means having a shaft extending through the housing and panel, a control dial mounted on the shaft exterior of the panel, and a terminal mounted by the housing having electric contact with the second element through the housing and shaft.

In witness whereof I affix my signature.

SAMUEL HAROLD SMITH.
